COMBINATION PUMP

Walter L. Knott, Los Angeles, Calif., assignor to
Lester B. Clark, Houston, Tex.

Application June 21, 1945, Serial No. 600,750

2 Claims. (Cl. 103—179)

1

The invention relates to a combination pump of the type used in producing liquid from wells.

There are generally two types of pumps utilized in pumping wells, the type including a working barrel and a plunger for reciprocating therein, and the type generally known by the trade as a fluid packed pump where concentric sleeves slide one within the other to provide a seal.

Each of these pumps have their peculiar advantages and disadvantages due to leakage, wear, and the effect of foreign matter upon the parts. The present invention, however, contemplates a combination of the plunger and the working barrel type of pump with the concentric sleeve type of pump to produce a construction which appropriates the better features of each.

It is one of the objects of the invention to provide a combination fluid pack and plunger pump wherein the upper portion of the pump is sealed with a reciprocating sleeve construction and the lower portion of the pump constitutes a plunger working against iron surfaces so as to obtain a maximum sealing and wearing effect.

Another object of the invention is to provide a concentric sleeve type of pump wherein the sleeve is elongated to provide a plunger to operate in a working barrel.

Another object of the invention is to provide a deep well pump with an operating plunger whose upper end is sealed with a concentric sleeve.

Other and further objects of the invention will be readily apparent when the following description is considered in connection with the accompanying drawing, wherein—

Fig. 1 is a vertical sectional view of the pump installed and in operating position in the well.

Fig. 2 is a side elevation of the well equipped with the pump construction.

In Fig. 2 the well bore 3 has been drilled and equipped with a casing 4 having the usual casing head 5 thereon. A string of tubing 6 has been run into the well and is connected to the perforated strainer or screen 7 so that the liquid from the producing formation 7' may enter the tubing.

The tubing 6 is seen enlarged in Fig. 1 and is made up of the sections such as 8, 9, and 10 connected together with the couplings 11.

The pump construction is shown as having been incorporated in the section 8 and is made up of a lower bushing 15 having a tapered seat 16 therein so as to receive the standing valve 17. The standing valve carries the valve member 18 confined by a cage 19 so that when there is a suction above the valve, a flow of liquid from below the

standing valve will move therethrough as indicated by the arrow 20. This standing valve may have the threaded pin 21 thereon by which it may be removed or inserted.

It is a well recognized fact that steel working against an iron surface provides a combination which will form a seal and will result in long continued service. The iron surface is provided herein as being made up of a plurality of members 25 disposed within the tubing section 8. Any desired number of these members may be applied end to end relative to each other, each member preferably having a recessed area 26 to receive the extension 27 of the next member 28 thereabove. Each of these members has an opening therethrough so as to provide a working surface 30 which is equivalent to the usual working barrel in a plunger type of pump.

The plunger in this invention is in the form of an elongated pipe or sleeve 32 preferably made of steel whose outer surface 31 is arranged for reciprocating movement upon the inner surfaces 30 of the bushings such as 25 and 28. A number of these members may be placed end to end so as to provide a suitable length which may be up to 15 feet or 20 feet.

All of these members such as 25 and 28 are fitted within the tubing section 8 and then confined by the collar 33 so that they are firmly arranged in position. A retainer pipe 34 is threaded at 35 into the collar 33 so as to form a compact assembly. The coupling 36 connects the collar 33 to the tubing section 8.

The lower end of the working sleeve or tubing 32 preferably has a rounded lower end to guide the sleeve into position and carries a traveling check valve 38 which in operation will open as the plunger moves down but will close on the upward movement so as to create a suction in the chamber 39 above the standing valve 18 in order to draw in a new charge of liquid from the well on the up stroke. On the down stroke the standing valve 18 will close and the liquid which is thus trapped in the chamber 39 will be forced to pass upwardly through the traveling valve and into the hollow interior 40 of the sleeve 32.

The sleeve 32 is of a substantial length and projects above the collar 33 into the tubing section 9 and has the head 41 substantially held at 42 thereon.

This head 41 carries a cage 43 and the upper traveling valve 44 which tends to close the passage 40 on the up stroke and allows the flow of liquid through the plunger into the tubing area 45 on the down stroke. A string of sucker rods

46 is connected to this head to cause the reciprocation and pumping action of the sleeve 32.

Great difficulty is encountered in the usual type of plunger pump due to the fact that sand and other matter being pumped along with the oil tends to settle in the tubing when it is pumped into the enlarged area 45 of the tubing. One of the advantages of a concentric sleeve type of pump is that sanding up of the working barrel is avoided due to the concentric sleeve arrangement. The present invention therefore contemplates a construction to accomplish this advantage and an outer sleeve 50 is therefore substantially held in place at 51 on the outer periphery of the head 41 and is concentrically arranged relative to the working sleeve 32. This sleeve 50, however, is considerably shorter than the working sleeve 32 and in the lowermost position of the plunger, the lower end 52 of this sealing sleeve 50 will closely approach the collar 33 as best seen in Fig. 1. The sleeves 32 and 50 will be spaced apart to provide an annulus 54 therebetween. This annulus will be filled by the standing sleeve or tubing 55 threaded at 56 into the upper end of the collar 33. This provides an elongated sealing surface between the outer periphery of the upper end of the working sleeve 32 and the inner periphery of the sealing sleeve 50. If desired, vents or breather openings 58 may be provided in the inner working sleeve so as to accommodate the expansion and contraction of the annulus 54 during the reciprocating movements.

In actual operation the advantages of a plunger and working barrel type of pump are obtained due to the lower construction of the sleeve 32 while the efficiency and long service of a concentric sleeve type of pump are obtained from the combination of the sleeves 50 and 32.

What is claimed is:

1. A pump for wells including a tubing in the 40

well, a standing valve in the tubing, a plurality of iron bushings disposed in said tubing above said valve, said bushings being hollow to provide a working barrel, a collar in said tubing to anchor said bushings, a standing tube extending upwardly from said collar, a plunger including a head and a pair of concentric spaced tubes depending therefrom to seal on the inside and outside of said standing tube, the inner of said tubes being of a length to extend into said bushings to work therein whereby a combination sleeve packed and working barrel seal pump is provided.

2. A pump for wells including a tubing in the well, a standing valve in the tubing, a plurality of iron bushings disposed in said tubing above said valve, said bushings being hollow to provide a working barrel, a collar in said tubing to anchor said bushings, a standing tube extending upwardly from said collar, a plunger including a head and a pair of concentric spaced tubes depending therefrom to seal on the inside and outside of said standing tube, the inner of said tubes being of a length to extend into said bushings to work therein whereby a combination sleeve packed and working barrel seal pump is provided, said plunger having a pair of spaced traveling valves therein.
